CHARLES E. LONG, OF MINNEAPOLIS, MINNESOTA, ASSIGNOR OF ONE-HALF TO PUFFER-HUBBARD MFG. CO., OF MINNEAPOLIS, MINNESOTA, A CORPORATION OF MINNESOTA

REFRIGERATING DEVICE

Application filed September 30, 1929. Serial No. 396,334.

This invention relates to improvements in refrigerating and goods-display devices and is particularly concerned with a construction for increasing the refrigerating capacity and for causing cold air to be circulated over display shelves arranged intermediately of the sides of a case, and adjacent a cooling unit. Objects are to maintain the refrigerating circulation at a point well below the glass sides of the case; to raise the circulation cycle with reference to display shelves and pass cold air thereover; to dispose a pair of display shelves laterally one at each side of the refrigerating unit; to provide a flue between the shelves with extensions above the refrigerating unit; upon which extensions the shelves are mounted; to provide means whereby the top of the case, shelf extensions and shelves can be removed; to provide a relatively broad shelf and to arrange it at such height that bottles or other commodities can be stored beneath it and within the circulation zone; and generally to provide a very efficient arrangement whereby a circulation flue is provided between a pair of spaced shelves such that the goods displayed on the shelves is always well within the refrigerating zone, and such that the shelf supports and shelves are arranged as baffles to form a down-current flue through which the warmer air approaches the refrigerating unit.

Objects, features and advantages will appear in the description of the drawing forming a part of this application, and in said drawing:

The single figure represents a transverse section through a case, showing one embodiment of the invention.

Numeral 1 indicates the bottom of the case, numeral 2 the sides and numeral 3 generally indicates a removable top, which top is composed of sides registered with sides 2 of the lower portion of the first mentioned portion of the case. The top includes glass slide doors 5, a pair on each side slantingly arranged to permit view of the contents of the case. The roof of the case is indicated at 6. The present invention is not concerned with the exact cross-sectional contour of the case, but relates principally to the central shelf and circulat-

ing structures now to be described, and their relation to the walls of the case.

In carrying out the invention, a cooling unit 10 is located centrally of the transverse dimension of the case as shown, and this coil is arranged adjacent the bottom of the case or adjacent the bed so that the refrigerating cycle will take place well below the glass, to prevent frosting and refrigerating losses. At each side of and extending longitudinally of the refrigerating unit 10 is arranged a baffle and shelf support 11, the lower end 12 of which is spaced above the upper surface of the bottom 1 of the case as shown. These baffles are suitably held by a skeleton frame work including vertical elements 14 of strap metal having feet secured to the bottom of the case. The upper end of each element 12 has a tongue 16 adapted to receive a corresponding groove 17 of extensions 18 which rise above the level of the top 19 of the refrigerating unit 10. On each of the extensions 18 is mounted a shelf 20 and upon each shelf at a point inwardly with respect to the extension 18 is attached a vertical extension 21. The two extensions 21 form a kind of flue permitting flow of the warmer air downwardly towards the cooling apparatus. The circulating action is diagrammatically represented by the arrows. This shelf and baffle arrangement include important features of the invention.

It will be noted that the unit is arranged centrally of the case. A type of coil is employed which includes fine closely spaced vertical refrigerating plates, the vertical type of refrigerating being the most efficient. By the use of this vertical type of refrigeration a smaller unit can be employed and therefore more display space can be had for a given size of refrigerating chamber. An important feature is the arrangement of the shelves to form a flue and their arrangement so that they are continually within the refrigeration zone, and so that they are readily accessible through the doors of the cases. Another feature is the arrangement whereby the shelves can be removed to permit ready access to the refrigeration unit 10.

The extensions 18 and shelf elements 20

and 21 are secured together in this instance by means of straps 22 only one of which is shown in the drawing, although it will be understood that there are a series of these straps, securing the parts so that they may be removed by an upward movement. Therefore, a portion of this combination shelf and baffle unit is removably secured.

The walls of the refrigeration chamber may be formed and heat-insulated in any preferred manner. This particular item forms no part of the present invention.

Laterally of the central combined refrigeration and shelf unit are arranged racks each indicated by the numeral 25. These slatted elements are raised above the floor 13 to admit of cold air circulation beneath the slatted structures and upwardly between the slats.

An important feature of the invention includes the idea of arranging shelves at opposite sides of the refrigerating unit and of having the shelf supports form baffles for baffling the air in a manner to cause it to circulate laterally at each side of and upwardly around the baffles and shelves and then downwardly between the shelves toward the upper part of the refrigerating unit.

Another feature of the invention is the arrangement whereby a storage space 26 is provided into which a milk bottle 27 or other commodity can be arranged beneath the shelf and within the refrigerating zone.

It is my intention to claim any and all shelf-supporting or forming means which act to obtain and maintain a refrigerating circulation over the shelves and contents thereon. I believe myself the first to provide an arrangement of the goods display shelves about a refrigerating unit in which the shelf supports act as baffles for obtaining circulation over and across the shelves in a manner to baffle the air and cause it to always contact and remain in contact with the goods over a substantial period of time, and, therefore, whereby the cold air is caused to contact the goods on the shelves for a greater length of time, due partly to the baffling action of the shelf supports, and partly to the use of the vertical circulation principle obtained by vertical arrangement of the baffles and the vertical portions 21 of the shelf, or shelves.

The vertical elements 21 not only act to form a circulation passage, but act as guards to prevent small articles, on display on the shelf, from dropping onto the coil. If a grating only were used to connect the shelves, and if the elements 21 were omitted, articles would be placed on the grill, and air circulation would be obstructed.

I claim as my invention:

1. A device of the class described including a refrigerating chamber, a refrigerating unit, a pair of baffles arranged vertically one at each opposite side of the unit, and having their lower ends spaced from the bottom of

the chamber, said baffles extending above said refrigerating unit, and each having a shelf which partly overlies said unit, the said shelves being spaced apart to permit downward circulation of the air between said shelves and toward said refrigerating unit.

2. A device of the class described including a refrigerating chamber, a refrigerating unit, a pair of baffles arranged vertically one at each opposite side of the unit, and having their lower ends spaced from the bottom of the chamber, said baffles extending above said refrigerating unit, and each having a shelf, having a vertically disposed element at its back, said elements being arranged to permit circulation of air from above the shelves, downwardly between the shelves toward the refrigerating unit.

3. A device of the class described comprising a refrigerating chamber, a refrigerating unit arranged centrally of the chamber, vertical baffles arranged at each side of said unit, each having its bottom arranged above the level of the bottom of the chamber to provide a circulation space, and the bottom of each being arranged below the level of the bottom of the refrigerating unit and each baffle extending above the top of said refrigerating unit, each baffle having a horizontal shelf arranged over said refrigerating unit, and extending laterally therebeyond to form a storage space, each shelf having an upward extension, the upward extensions together forming a flue permitting flow of air from above downwardly between the shelves and toward the top of the unit.

4. A device of the class described including a refrigerating chamber, a refrigerating unit arranged within the chamber, vertically arranged partitions one at each opposite side of said refrigerating unit and extending above and below the same, but spaced above the floor of the chamber, shelves supported upon said baffles in a manner to form a flue leading downwardly toward the refrigerating unit, said baffles being sectional and arranged so that a portion of the baffle and the shelves can be removed to permit access to said refrigerating unit.

5. A device of the class described including a chamber having glass sides, a refrigerating unit within the chamber, baffles arranged adjacent the refrigerating unit and spaced from the side walls of the chamber to provide a passage adapted to direct circulation of air downwardly toward the middle of the unit, then in opposite directions to the sides of the unit, then downwardly then outwardly beneath the baffles and upwardly, and display shelves arranged immediately adjacent the baffles to form niches beneath the shelves in which goods may be received and be visible, through the glass sides of the case, and be easily accessible, and yet be within the circulation zone formed by the baffles.

6. A device of the class described including a refrigeration chamber and a refrigerating unit of the plate coil type therein, and means associated with the unit in a manner
5 to direct air circulation downwardly toward the middle of the tops of the plates and thence diagonally downwardly and outwardly in opposite directions across the faces of the plates toward the floor of the chamber.
- 10 7. A device of the class described including a refrigeration chamber, and a refrigerating unit of the plate coil type therein, baffles one at each side of the unit arranged there-adjacent and lengthwise thereof and having
15 their lower edges spaced from the floor of the chamber, and having means arranged above the unit to direct warmer air circulation downwardly toward the middle of the tops of the plates, so that the air will there-
20 after travel diagonally downwardly and outwardly across the faces of the plates in opposite directions and beneath the baffles.

In witness whereof, I have hereunto set my hand this 18th day of September 1929.

CHARLES E. LONG.
